UNITED STATES PATENT OFFICE.

WILLIAM WALL TALBOT, OF NEW YORK, N. Y.

SAFETY GUARD ATTACHMENT FOR VEHICLES.

1,148,553.

Specification of Letters Patent. Patented Aug. 3, 1915.

Application filed February 8, 1913. Serial No. 746,989.

To all whom it may concern:

Be it known that I, WILLIAM WALL TALBOT, a citizen of the United States, residing at New York, in the county and State of New York, have made a certain new and useful Invention in Safety Guard Attachments for Vehicles, of which the following is a specification.

This invention relates to safety guard attachments for vehicles.

The object of the invention is to provide a safety attachment for automobiles or other vehicles, which is simple in construction and efficient in operation and which is capable of ready attachment to any type or design of vehicle.

A further object is to provide a safety attachment of the character referred to wherein a curtain or its equivalent is automatically projected downwardly and forwardly in case of collision of the vehicle with a person or object whereby to form a safety receptacle to receive and sustain the person or other object if thrown down by the collision; thereby affording a safety means to prevent the vehicle from running over such person or object.

A further object is to provide a main and an auxiliary curtain device for the purpose of increasing the efficiency of the device as a means of preventing injury to pedestrians in case of collision, the curtain devices being automatically tripped and projected into position to receive and sustain the pedestrian in case of being thrown by the impact of collision.

Other objects of the invention will appear more fully hereinafter.

The invention consists substantially in the construction, combination, location and relative arrangement of parts, all as will be more fully hereinafter set forth as shown in the accompanying drawings and finally pointed out in the appended claims.

In the accompanying drawings; Figure 1 is a view in top plan, parts being broken out and parts shown in horizontal section, showing a safety guard attachment for vehicles in distended position for use as applied to the front end of a vehicle such as an automobile. Fig. 2 is a view in side elevation showing a portion of the front end of a vehicle and the application thereto of a safety guard attachment embodying my invention, parts being shown in section and the safety curtains and their operating rods

and frame being shown in full lines in retracted or restrained position, and in dotted lines in projected position. Fig. 3 is a fragmentary broken detail view showing the lower curtain roll and casing in transverse section, and the tripping mechanism for releasing the curtain operating rods. Fig. 4 is a broken detail view in horizontal section on the line 4, 4, Fig. 5, of one of the guard curtain roll casings and its ratchet and pawl detent. Fig. 5 is a similar view in vertical transverse section of the same on line 5, 5, Fig. 4. Fig. 6 is a broken view in top plan, showing one form of adjustable bracket mounting for the safety attachment embodying my invention. Fig. 7 is a similar view in side elevation of the construction shown in Fig. 6, the buffer spring and its casing being in section. Fig. 8 is a similar view in front elevation of the construction shown in Figs. 6 and 7. Fig. 9 is a view similar to Fig. 6, showing a modified structure of bracket mounting. Fig. 10 is a similar view in front elevation. Fig. 11 is a similar view in side elevation, parts being shown in section.

The same part is designated by the same reference sign wherever it occurs throughout the several views.

The extensive use of motor vehicles, and particularly of the modern automobile is attended with numerous instances of fatalities to pedestrians and others by reason of collisions or the automobile striking, knocking down and running over persons on the streets. This is particularly the case where the automobiles are driven at high speed on crowded streets, or are operated by incompetent, reckless or careless drivers.

Many different forms and constructions of devices intended to reduce accidents due to the operation of automobiles have been proposed in the way of bumper operated fenders, life guards and the like, but so far as I am aware no practical or successful device of this nature has been brought out on the market. That a need exists for such a device is apparent from the fact that almost daily fatal accidents of the nature referred to occur, and the attention of legislatures is being directed to the enactment of laws having in view the prevention, elimination or at least the reduction of such accidents. Moreover, the accident insurance rates for the operation of automobiles are based largely on the risks incurred in the

operation of such machines, and a practical, successful construction of safety guard which will reduce the risk and danger of operation of automobiles will result in a material reduction in the insurance rate.

- It is among the special purposes of my invention to provide an automatic safety guard attachment for automobiles which is simple in construction and efficient in use and which
- 5 is capable of ready application to any type of machine, wherein, in case a person is struck by the machine while running, a curtain is projected forwardly and downwardly into position to form a receiver or receptacle
- 10 to catch the person collided with and support such person, thereby preventing the machine from running over such person. It sometimes happens that when a machine strikes a person the victim of the accident
- 15 may be thrown too high onto the machine to be caught by the safety curtain but will land on the radiator or other portion of the front end of the vehicle, and will roll or be thrown off to the ground before the machine
- 20 can be stopped and not only be injured by the fall but may so fall as to be caught underneath the machine or its wheels and still more serious injury be inflicted. Therefore, in accordance with my invention, I propose
- 25 to employ an upper auxiliary safety curtain which is operated in conjunction with the lower curtain, and which is simultaneously therewith projected downwardly and forwardly into position to form a safety receptacle to receive and hold a person struck and thrown by the machine. I also propose to construct and mount the safety attachment in such manner as to perform the function of the usual bumper, such as is ordinarily carried at the front ends of automobiles, and to provide means for the adjustment of such bumper.

With these and other objects and purposes in view I will now describe the construction

45 shown in the accompanying drawings as one form of practical device for carrying the same into practical operation.

In the drawing 12 designates a portion of the front end of the chassis or frame of a

50 vehicle, such as an automobile, and 13, the usual body spring therefor. Suitably mounted upon the chassis at opposite sides of the machine are vertical standards 14,

55 14, in the upper ends of which is mounted a curtain roller casing 15, in which is journaled a curtain roller 16, onto, and from which a safety curtain 17 is designed to be rolled. Inasmuch as the curtain 17, roller 16 and casing 15, as well as the associated

60 ratchet wheel and pawl are the same in construction for the upper curtain as for the lower curtain, presently to be described, a description of the details of the one will answer for that of the other and these features will therefore be more fully described

in connection with the lower curtain and Figs. 2, 3, 4 and 5. It is sufficient for the present to say that the curtain 17 is attached at one end to the roller 16. At its other end the curtain 17 is attached to the portion 18 of a rocking frame, the side members 19, 19, of which are journaled to rock or swing upon a rod 20, extending transversely across the machine between the standards 14. When the curtain frame 18, 19, is in its vertical or retracted position, as shown in full lines in Fig. 2, with the curtain 17 rolled up on its roller 16, within the casing 15, said frame is maintained in that position against the action of springs the tension of which is exerted to normally rock or throw said frame forwardly and downwardly into horizontal position, as shown by dotted lines in Fig. 2. A convenient arrangement of springs for this purpose and operation is shown wherein rods 21 are pivotally connected to brackets 22, carried by the side portions 19 of the curtain frame, said rods being arranged to work loosely through openings in the upturned ends 23 of brackets 24 carried by the chassis, a coiled spring 25, being interposed between the end 23 and a collar 26, carried by each rod. With this arrangement the tension of the springs is constantly exerted upon the curtain frame, when in its upright or vertical position, tending to rock the same sharply downwardly into horizontal position when the restraining means which hold said curtain frame in upright position is released. Of course when the curtain frame is rocked down into horizontal position, that is, when the restraining or detent mechanism therefor is released the upper curtain 17 is unrolled from its roller and drawn out from

70 75 80 85 90 95 100 105 110 115 120 125 130

casing 15 into the position indicated in dotted lines in Fig. 2, and in full lines in Fig. 1, to form a receptacle or safety receiver for a person thrown into the same.

Pivotally connected at their upper ends to the portion 18 of the upper curtain frame at each end thereof, as at 27, is a member 28, which, in the particular form shown, but to which my invention as defined in the claims is not to be limited or restricted, is in the form of a rack bar. The two bars 28, at opposite sides of the machine are connected together by a transverse bar 29, at their lower ends, and to this transverse bar 29, is connected the lower or free end of the lower curtain 30. This curtain is rolled up on and from a roller 31, mounted in a casing 32, which is supported in adjustable hanger arms 33, from a supporting bumper bracket 34, mounted on the side members 12 of the chassis. The casing 32 is formed with a slot 35, through which the curtain works. Upon the roller 31 is mounted a ratchet wheel 36, with which cooperates a pivoted

120 125 130

détent pawl 37. Suitable means such as a

screw 38 may serve to so adjust the pawl 37 as to withdraw and hold the same in disengaged relation to the ratchet wheel 36. The purpose of this construction is to enable the 5 curtain to be easily rolled up on its roller 31, by applying a suitable wrench or other convenient tool to the end 39, of the roller. While the curtain is being rolled up on the roller the pawl 37 is in engaging relation 10 with the ratchet wheel 36 to hold the curtain in rolled up condition. After the curtain has been completely rolled up and the parts restored to their normal retracted position ready to be projected into position 15 for use when again tripped or released the screws 38 are manipulated to withdraw the pawls from engaging relation with respect to the wheels 36, so as to leave the device free for the curtain to be projected when 20 tripped. As above explained the construction and arrangement of the lower curtain, its roller, casing and ratchet mechanism, as just described, is the same for the upper curtain as for the lower one.

25 The parts of the safety attachment so far described may be held in their retracted positions against the action of the springs 25, and may be released for use, in case of accident or collision, in many specifically 30 different ways. A simple arrangement is shown wherein the front end of each chassis member 12 carries a stud 41 on which is journaled a gear wheel 40. Each rack bar 28 engages a gear wheel 40. Loosely mounted on each stud 41 is a rocking keeper 42, arranged to engage over the rack bar 28 to retain the same in engagement with the gear wheel 40. By loosely pivoting the rocking keeper 42, the rack bars 28 are permitted a desirable range of tilting movement, while being projected endwise, without binding upon the gears. The gears 40 are each engaged by a hand operated pawl 43, which prevents reverse rotation of said 40 gear when in engaging relation therewith, but which may be thrown out of engagement when the apparatus is to be reset ready for use. The restraining detent to hold the safety device in normally retracted position ready to be tripped, in the particular form shown, to which however my invention as defined in the claims is not to be limited or restricted, comprises a detent lug or projection 44, which engages the gear 40. 45 This detent is carried by a rocking frame which includes a bar 45, extending transversely across the machine, and arms 46, which extend upwardly and forwardly over the curtain casing 32, and carry the trip bar 47. In case of a collision with a pedestrian the trip bar 47 is forced backwardly thereby rocking the arms 46, and rod 45, and releasing the detents 44 from engagement with the gears 40, and thereupon the frame 50 55 60 65 70 75 80 85 90 95 100 105 110 115 120 125 130

against the action of the springs 25, by the engagement of the detent 44 with the gears 45, is instantly swung downwardly by the springs 25 into the position shown in full lines in Fig. 1 and in dotted lines in Fig. 2. 70 This movement of frame 18, 19, draws out the upper curtain 17, while at the same time the rack bars 28 are projected, forwardly and downwardly, thereby drawing out the lower or main curtain 30, the curtains 30, 75 17, being thus brought into position to catch and hold the victim struck by the machine and thus prevent the serious injury of such victim falling under and run over by the vehicle.

If desired the lower ends of the rack bars may carry rollers or other suitable forms of runners, indicated at 48, to facilitate the movement thereof over the surface of the ground in case, through the weight of the 80 person thrown on to the lower curtain or otherwise the lower ends of the rack bars should come in contact with the ground. The lower ends of said bars may be turned or curved upwardly, as shown, for a similar 85 purpose.

In order that the apparatus may serve the further purpose of a yielding bumper I propose to mount the lower curtain casing and roller in such manner as to be yieldingly 90 pressed forwardly of the machine. Many different constructions of mountings to accomplish this purpose may be employed. I have shown various arrangements for the purpose. In Figs. 1, 2, 3, 6, 7 and 8, one 100 arrangement is shown wherein the bracket 34, which support the curtain carrier or casing arms 33, is carried by parallel links 49, 50, which are pivotally connected to said bracket at their upper ends, and to the supporting plate 42, at their lower ends. One of said links, as 49, is in the form of a bell crank lever, the short arm 51, of which has a rod 52 pivotally connected thereto, which is arranged to extend into a casing 53 and has a collar 54 at its end against which bears a coil spring 55, the other end of said spring bearing against the cap 56 which closes the end of said casing. The tension of this coil spring is exerted through the collar 54 and rod 52 tending to rock the bell crank lever 51, 49, in a direction to maintain the bracket 34, and with it the lower curtain casing 32, yieldingly pressed forwardly. In case of a severe collision of the machine with any object 110 115 120 125 130

The desired adjustment of the bracket 34 and of the curtain casing 32 may be secured in many different ways. As shown, provision is made for vertical adjustment by providing the plate 42 with vertical slots 57, through which extend the bolts 58, by means of which said plate is secured to the 130

chassis. Further adjustment of the curtain casing 32 is secured by providing the carrying arms 33 with a hub portion having serrated teeth arranged to be clamped against 5 a co-operatingly serrated hub face, as indicated at 60, these hub faces being clamped together. By loosening up the clamp bolt which holds these hub faces together the arms 33 may be adjusted angularly to any 10 desired position and then securely clamped in their adjusted relation. The hub portion 61, may also be mounted for angular adjustment about the axis of the vertical bolt 62, by means of which it is supported in the 15 end of the bracket 34.

In Figs. 9, 10 and 11, I have shown a slightly different bumper construction which, on account of its simplicity, I prefer to use in many cases. In this arrangement the 20 lower curtain casing will be carried by a hanger 63 which is mounted for adjustment transversely of the machine by a slot and bolt connection, indicated at 64, with a casting 65. This casting includes a chamber in 25 which is seated a coil spring 66, which engages a washer 67, carried by a bolt 68, the latter forming means for adjustably securing the casting 65, to a carrier member 67. The casting 63 is provided with a rounded 30 seat socket in which is received a similarly shaped shoulder or projection on the member 67, these parts being yieldingly held in seated relation by the bolt 68 and spring 66. This construction permits a desirable range 35 of flexibility and relative yielding movement of the parts which prevents binding thereof. The member 67 telescopes into the chamber of a casing 69, in which is contained a coil spring 70, which bears at one end against the 40 bottom wall of casing 69, and at the other end against a shoulder on the member 67, so as to normally press the member 67 forwardly. Limit stops or lugs 71, 72 serve to limit the extent of forward movement of 45 the member 67 and the parts carried thereby. The casing 69 is carried by a clamp member 73, which is mounted for angular adjustment on a plate 74, which in turn is vertically adjustable by means of slotted 50 clamps 75 which secure the same to the chassis member 12. This provides for universal adjustment of the curtain casing and enables the same to perform the function of a bumper which yields under the influence of 55 a severe collision and takes up and absorbs the resulting shock without doing injury to the victim of the collision or to the machine.

It is believed that the operation of the 60 safety attachment embodying my invention as shown and above described will be fully understood and comprehended by persons skilled in the art.

Having now set forth the objects and pur- 65 poses of my invention and constructions

embodying the principles thereof, what I claim as new and useful and of my own invention, and desire to secure by Letters Patent is:—

1. In a safety attachment for automobiles 70 and other vehicles, a curtain, a roller therefor, a rod connected to the lower edge of the curtain, bars connected to the ends of said rod, means for yieldingly retaining said bars in retracted relation and means positioned in advance and independent of said roller and said curtain for tripping said retaining means to permit said bars to be projected forwardly and downwardly to carry the curtain into position to form a scoop re- 80 ceptacle.

2. In a safety attachment for automobiles or other vehicles, a casing mounted at the front end of the vehicle, a roller journaled in said casing, a curtain adapted to be rolled up on said roller, a rod connected to the free end of said curtain, bars connected to said rod, means to project said bars diagonally downwardly and forwardly, a detent for restraining said projecting means, and means 90 positioned in advance and independent of said casing for releasing said detent.

3. In a safety attachment for automobiles or other vehicles, a casing mounted at the front end of the vehicle, a roller journaled 95 in said casing, a ratchet gear carried by said roller, a releasable pawl engaging said gear, a curtain adapted to be rolled up on said roller, means under tension connected to the free end of the curtain and adapted, 100 when released, to project the curtain downwardly and forwardly, a detent for restraining said tension means, and means for releasing said detent.

4. In a safety attachment for automobiles 105 or other vehicles, a casing, a roller journaled therein, a curtain adapted to be wound on said roller, spring pressed bars connected to the free end of the curtain, a detent for restraining said bars, and a fender bar independent of said casing extending in advance of the vehicle and connected to the detent to release the same.

5. In a safety attachment for automobiles or other vehicles, a curtain mounted at the 115 front end of the vehicles, bars connected to the free end of said curtain, said bars having upturned ends, means for exerting a tension on said bars to project the same endwise forwardly and downwardly, a detent 120 to hold said bars in retracted position, and a fender bar positioned in advance of the curtain roller to release said detent in case of collision.

6. In a safety attachment for automobiles 125 or other vehicles, a curtain mounted at the front end of the vehicle, rack bars connected to the free end of the curtain, a spring acting on said bars tending to project the same endwise forwardly and downwardly, gears 130

engaged by said bars, detents engaging said gears, and a fender bar positioned in advance of the curtain to release said detents.

7. In a safety attachment for automobiles 5 or other vehicles a curtain mounted at the front end of the vehicle, rack bars connected to the free end of the curtain, springs acting upon said bars to project the same endwise forwardly and downwardly, gears 10 engaged by said bars, keepers for maintaining the engagement of said bars and gears, detents for said gears, and a fender bar connected to the detents to release the same, said fender bar being positioned in advance 15 of the curtain.

8. In a safety attachment for automobiles or other vehicles, a casing means for adjustably supporting the same at the front end 20 of the vehicle, a curtain secured at one end in said casing, means connected to the free end of the curtain to project the same forwardly and downwardly from the casing, a 25 detent for restraining said projecting means, and a fender bar positioned in advance and independent of the casing for tripping said detent in case of collision.

9. In a safety attachment for automobiles or other vehicles, a casing, a yieldingly 30 mounted support therefor at the front end of the vehicle, a curtain secured at one end in said casing, spring pressed means connected to the free end of the curtain to project the same forwardly and downwardly, a 35 detent for restraining said projecting means and a fender bar positioned in advance and independent of said casing and connected to the detent for releasing the same.

10. In a safety attachment for automobiles or other vehicles, an upper curtain and a lower curtain mounted at the front end 40 of the vehicle, means connecting the lower ends of said curtains, restraining devices for retaining said connecting means under tension in retracted position and tripping mechanism for releasing said restraining 45 means.

11. In a safety attachment for automobiles or other vehicles, an upper and a lower curtain mounted at the front end of the vehicle, a spring pressed frame connected 50 to the free end of the upper curtain, bars connected to said frame and to the free end of the lower curtain, a detent for holding said frame in retracted position, and means for tripping said detent. 55

12. In a safety attachment for automobiles or other vehicles, an upper and a lower curtain mounted at the front end of the vehicle, a spring pressed rocking frame connected to the free end of the upper curtain, bars pivotally connected to said rocking frame, said bars connected at their lower ends to the free end of the lower curtain, a 60 detent to hold said frame and bars in retracted position, and means for tripping said detent to release the same. 65

In testimony whereof I have hereunto set my hand in the presence of the subscribing witnesses, on this 3rd day of February A. D. 1913.

WILLIAM WALL TALBOT.
